UNITED STATES PATENT OFFICE.

GEORGE A. SCHREINER, OF TROY, NEW YORK, ASSIGNOR TO CLUETT, PEABODY & CO., INC., OF TROY, NEW YORK, A CORPORATION OF NEW YORK.

DIE HOLDER FOR FOLDING MACHINES.

Application filed October 21, 1921. Serial No. 509,369.

To all whom it may concern:

Be it known that I, GEORGE A. SCHREINER, a citizen of the United States of America, and resident of Troy, in the county of Rensselaer and State of New York, have invented new and useful Improvements in Die Holders for Folding Machines, of which the following is a specification.

This invention concerns folding machines of the type commonly employed for folding collar blanks and the like and relates more particularly to the die plate over which the material is folded and to the means for supporting such die plate.

In the operation of folding a collar or cuff blank, the die plate is placed upon the material and the entire marginal edge of the blank is then turned up over the edge of the die plate and subjected to pressure. To permit removal of the die plate from beneath the folded margin of the blank it is necessary that the die plate be made to collapse, and to this end the plate is commonly constructed of a plurality of parts each of which is mounted upon an independent carrier block. These blocks, with their portions of the die plate, are urged in opposite directions by suitable spring means, whereby normally to maintain the die plate in fully expanded condition but permitting collapse of the same for removing the folded blank. This arrangement is in general satisfactory but under some circumstances it is found that the action of the folders in wiping the material inwardly over the edges of the die plate tends partially to collapse the die plate thereby producing defective work. Moreover at times, by reason of wear of the parts or accumulation of dust and lint therein, it may happen that the die plate, after being collapsed for removing the folded blank fails to return to its fully extended position, thus again resulting in improperly folded work.

The principal object of the invention is to provide for positively locking the die plate members in fully extending position during the folding of the material thereover and also to prevent the positioning of the die plate in operative relationship to the folding mechanism until such die plate has been fully extended.

In accordance with this object the invention may be briefly stated to consist in pro-

viding the carrier blocks for the relatively movable elements of the die plate with oppositely disposed abutment members between which a rigid locking block may be positioned during the wiping operation, whereby positively to retain the relatively movable elements of the die plate in fully extended position. This locking block may if desired be provided with a guiding stem projecting toward the bed of the machine and normally urged in such direction by a spring or equivalent means, the arrangement being such that when the die carrier is raised the spring serves to move the block from between the abutment members but when the end of the stem strikes the bed plate or the blank thereon during the descent of the die carrier the block is moved into the space between such abutments. If however, during the downward movement of the die carrier, the abutments for any reason should be abnormally close together, as by reason of failure of the die elements to assume normally extended position, the block is thus prevented from passing between the abutments and the descent of the die carrier toward operative position is arrested.

In the accompanying drawings there is illustrated by way of example one embodiment of means whereby the above object may be carried into effect. In such drawings,

Fig. 1 is a fragmentary front elevation of a folding machine having the present invention applied thereto;

Fig. 2 is a fragmentary transverse cross section to enlarged scale through the bed plate die carrier on a line such as *a—b* of Fig. 3; and

Fig. 3 is a longitudinal vertical cross section through the die carrier.

The machine table 1 is carried on suitable supports 2, 3 and is provided with a bed plate 4 upon which the work is placed to be folded. Pivotedly mounted on brackets 5 secured to the frame of the machine is an arm 6 which serves to support the die carrier and the die plate carried thereby. The arm 6 may be raised or lowered manually or by the use of any desired mechanical arrangement such for example as that disclosed in the patent to Brown, No. 1,053,477, February 18, 1913. At its upper extremity the arm 6 is bifurcated to provide spaced mem-

bers 7, 8, and secured to such members is an inverted channel bar 9. This bar may be connected to the members 7, 8 by bolts 10, or in any other desired manner.

5 Within the channel of the bar 9 are arranged die carrying blocks comprising the members 11, 12, and 13, 14 respectively. While for convenience of manufacture these blocks are made in two parts, it is contemplated that they might be made as single integral members, if desired. The upper wall of the channel bar 9 is provided with aligned slots 15, 16 through which pass screws such as 17, 18 engaging threaded 10 openings in the members 11, 13 respectively. The die carrying blocks are thus secured in position in the channel of the member 9, the screws 17, 18 serving to retain them in position while permitting them to move longitudinally of the channels. Adjustable stop screws 19, 20 may be provided for limiting the outward movement of the respective blocks in the channel.

25 Within the channel and intermediate the movable die supporting blocks is a stationary block or housing 21 secured to the member 9 by means of bolts 22. The block 21 is provided with substantially aligned guide openings for the reception of rods 23, 24 respectively. The remote ends of the respective rods are fixedly secured in the members 11, 13 of the respective die blocks. Surrounding the rods 23, 24 are coil springs 25, 26 respectively, such springs being so arranged as normally to urge the movable die carrying blocks in opposite directions. At their inner ends, the rods 23, 24 project into a chamber 27 within the housing block 21.

30 40 A rod 28 extends vertically through the chamber 27, being guided for sliding movement in openings in the member 9 and in the lower wall of the housing block 21. The upper end of the rod 28 is also guided in an opening in a bracket 29 secured to the member 9 by means of a screw 30. A collar 31 is adjustably secured to the rod 28 at a point above the upper surface of the bar 9 and interposed between such collar and the 45 under surface of the bracket 29 is a coil spring 32. This spring is so arranged as normally to urge the bar 28 in a downward direction.

50 The members 12 and 14 of the die block 55 are provided with openings such as 33, while the fixed block is provided with openings such as 34, these openings serving for the reception of pins such as 35, 35^a and 36 carrying the die plate sections 37, 38 and 39 respectively. The several pins may be secured in position within the openings by means of set screws 40 or any other desired manner, it being noted that the several sections of the die plate are normally arranged 60 in the same plane. Within the chamber 27,

in the housing block 21 is arranged a stop member 41, consisting of a block pinned to the rod 28 and movable therewith.

65 On the normal position of the parts, the stop member 41 occupies a position such as 70 shown in Fig. 3 wherein its upper surface is below the rods 23, 24. In this position of the parts, also, the lower end of the rod 28 projects slightly below the lower surface of the die plate section 29, passing 75 through a suitable opening therein. In Fig. 3 the die carrying blocks are shown as in fully extended position, wherein the adjacent ends of the rods 23, 24 project but slightly into the chamber 27, thus providing 80 sufficient space between them for the reception of the stop member 41. With the parts as thus arranged, upon lowering of the arm 6 to bring the extensible die plate 85 into position for cooperation with the bed plate 4, the lower end of the rod 28 will strike the bed plate or the work thereon prior to the final positioning of the die plate. The completion of the downward movement will then carry the member 41 90 upwardly into the space between the adjacent ends of the rods 23, 24. During the folding operation, the parts remain in this position and as the space between the members 23, 24 is substantially filled, there is no 95 possibility of relative movement of the die carrying blocks such as might permit collapse of the die plate. When the folding operation has been completed and the arm 6 is raised, the spring 32 immediately acts 100 to depress the rod 28, carrying the stop member 41 from between the ends of the abutment members 23, 24, thus permitting the operator to collapse the die plate whereby to remove the work therefrom.

105 If for any reason either or both of the die carrying blocks should remain in its inward position after the removal of the work as for example by reason of breakage of one of the springs 25, 26, or by the 110 accumulation of lint or dirt in the guideways such as to prevent the springs from acting properly, the inner end of one or both of the rods 23, 24 would extend inwardly into the chamber 27 in such manner 115 as to prevent upward movement of the stop member 41. Upon downward movement of the arm 6 such as to cause the projecting end of the rod 28 to strike the bed plate or the work, any relative movement between the 120 rod and bar 9 would be prevented by engagement of block 41 with one or both of the rods 23, 24, and thus the downward movement of the arm 6 would be limited. The attention of the operator would thereby be 125 called to the improperly positioned die members and the possibility of producing defective work by reason of the improper positioning of such members is thus avoided.

130 While the invention has herein been

shown as comprising a specific arrangement of die carrying blocks and locking means therefor, it is contemplated as within the scope of the present invention that various changes and rearrangements in parts might well be made without departing from the spirit of the present invention.

Having thus described the invention and the mode of operation thereof, what I claim and desire to secure by Letters Patent of the United States is:

1. A folding machine comprising an expandible die plate, means constantly tending to expand the die plate, and means for positively maintaining said die plate in fully expanded position during the folding operation.

2. A machine of the class described having a die plate comprising an extensible element, resilient means normally operable to maintain said element in extended position, and positive means for maintaining said element in such position during the folding operation.

3. A folding machine having a die plate comprising relatively movable members, spring means normally urging said members in opposite direction, abutment elements associated with the respective members, and a member interposable between said elements whereby positively to limit approach of said members.

4. A blank folding machine having a die holder comprising a pair of relatively movable die blocks, a die plate member secured to each of said blocks, spring means normally tending to separate said blocks, opposed abutment elements carried by the respective blocks, and a member movable into the space between said elements whereby to limit approach of said blocks.

5. A die holder for folding machines comprising a support provided with a guide element, a die block slidably engaging said guide element, spring means normally urging said block in a predetermined direction, a die plate member secured to the block, an abutment carried by said block, and a stop member movable into position for engagement by said abutment whereby positively to prevent movement of said block in opposition to said spring.

6. A die holder for blank folding machines comprising a support provided with aligned guideways, die blocks slidably guided by the respective guideways, die plate members carried by the respective die blocks, rods secured to the respective die blocks and extending toward each other, springs enclosing said rods and normally urging said blocks in opposite directions, and a block slidably guided for movement into and out of the space between adjacent ends of said rods.

65 7. A die holder comprising a slidable die

block having a die plate member secured thereto, a rod extending from said block, means for guiding said rod, a spring normally urging said block away from such guide means, and a member interposable in the path of movement of the end of said rod for limiting movement of the block toward said guide means.

8. A folder die holder comprising a support, a die block slidably guided thereby, a rod secured to said block, spring means urging said block in a predetermined direction, a bar slidably guided in a suitable opening in said support to move in a path transverse of that of said rod, and a member carried by said bar and operative to limit movement of said rod and the block in opposition to the spring.

9. A folding machine having a die holder comprising a support, a pair of oppositely slidable blocks carried by the support and provided with die plate members, springs normally urging said blocks in opposite directions, a bar interposed between said blocks and slidably guided in said support for movement in a path transverse of that of the blocks, a spring normally urging said bar in a downward direction, and a stop member carried by said bar and constructed and arranged to limit approach of said blocks upon movement of said rod in opposition to its spring.

10. A die holder for folding machines having a support comprising a plate provided with spaced, aligned slots, and a housing secured thereto and between said slots, blocks having projecting elements slidably engaging the respective slots, oppositely directed rods secured to the respective blocks and extending into said housing, a bar slidably guided in aligned openings in said plate and housing respectively, the lower end of the bar normally projecting below the housing, and a stop block secured to said bar within the housing and movable into and out of the space between the adjacent ends of said rods.

11. A folding machine having a movable die holder provided with an expandible die plate resilient means for expanding said die plate, and means opposing movement of said die holder into folding position if said die plate is not fully expanded.

12. A folding machine having a bed plate and a die holder movable into operative position relative thereto, said die holder being provided with an expandible die plate comprising relatively movable members, resilient means normally urging said members in opposite directions, and means limiting movement of said die holder toward the bed plate provided the die plate is not fully expanded.

13. A folding machine having a bed plate and a die holder movable toward and from

the same, a collapsible die plate carried by said holder, resilient means normally operative to expand said plate, a stop member comprising a bar guided for movement in openings in said holder, spring means normally urging said bar downwardly whereby to cause its lower end to project below the bottom of the holder, an abutment element secured to said bar, and means engageable with said element upon collapse of said die plate whereby to prevent relative movement of said bar and holder.

Signed by me at Troy, N. Y., this 27th day of September 1921.

GEORGE A. SCHREINER.
